GEORGE McD. JOHNS, OF ST. LOUIS, MISSOURI.

PUMP.

1,367,702.

Specification of Letters Patent.

Patented Feb. 8, 1921.

Application filed January 24, 1919. Serial No. 272,944.

To all whom it may concern:

Be it known that I, GEORGE McD. JOHNS, a citizen of the United States, residing at the city of St. Louis, State of Missouri, have 5 invented certain new and useful Improvements in Pumps, of which the following is a specification, reference being had to the accompanying drawing, forming a part thereof.

10 This invention relates generally to pumps and, more particularly, to certain new and useful improvements in water pumps.

The chief objects of my present invention are to provide a pump and, more especially, 15 a pump of the class stated which is simple, compact, rugged, and durable in form and construction and dependable and efficient in operation with economy and low cost of maintenance or upkeep; to provide a pump 20 of the class stated in which the several parts are adapted for ready assemblage and are conveniently interchangeable and replaceable in case of wear, breakage, and the like; to provide a water-pump in which a base 25 for the cylinder or cylinders and the suction and discharge manifolds are cast or otherwise formed as a unitary structure, the base being selectively of a size to accommodate one or more cylinders agreeable with the 30 desired capacity of the finished pump and the manifolds being provided correspondingly with independent pairs of port-openings for said one or more cylinders; to provide a water-pump comprising, as a complete, integral unit, an element or part 35 adapted to form a combined valve-chamber and a cylinder-connection, whereby each cylinder, with its valves, is structurally independent of the other cylinders, and to provide, 40 in connection with the one or more combined valve-chamber and cylinder-connection units, simple and efficient means whereby each of said units may be demountably fastened or secured independently to 45 and upon the base of the pump; and to generally simplify the construction of and improve upon pumps especially of the class mentioned.

With the above and other objects in view, 50 my present invention resides in the novel features of form, construction, arrangement, and combination of parts hereinafter described and afterward pointed out in the claims.

55 In the accompanying drawing, Figure 1 is a side elevational view of a

three-cylinder pump constructed in accordance with and embodying my invention in preferred form;

Fig. 2 is an enlarged fragmental plan 60 view of the pump, partly in section on approximately the line 2—2, Fig. 1;

Fig. 3 is a transverse sectional view of the pump on approximately the line 3—3, Fig. 2;

Fig. 4 is a fragmental end elevational view of the pump;

Fig. 5 is an inverted fragmental plan of the pump-base, showing the suction and discharge manifolds and the cylinder-drain; 70

Fig. 6 is an enlarged broken longitudinal sectional view of the base on approximately the line 6—6, Fig. 5; and

Fig. 7 is a view similar to Fig. 6 on approximately the line 7—7, Fig. 5. 75

Referring to the said drawing, in which like reference characters refer to like parts throughout the several views, the base of the pump comprises a top or body-portion 1, which is preferably, as shown, of rectangular oblong plate formation, integrally provided at and around its four margins with a supporting substantially right-angled flange or wall 2. As shown most clearly in Figs. 2 and 6, the base-plate 1 is formed selectively 80 in accordance with the desired capacity of the particular pump with any desired number of port-openings or apertures 3 arranged in pairs aligned transversely of the base, as seen in Fig. 2, and at spaced intervals longitudinally of the base, as also seen in Fig. 2, each transversely aligned pair of ports 3 being adapted for connection and co-operation with a cylinder and the base of the three-cylinder pump here illustrated being consequently formed or provided with three pairs 90 of the ports 3.

Forming integral parts of the base and extending longitudinally thereof beneath the plate or top 1, as seen in Figs. 3 and 5, 100 are suction and discharge manifolds 4 and 5, respectively, manifold 4 being in open communication with one row of the ports 3 and the manifold 5 being in open communication with the other row of ports 3. Each manifold 4, 5, is permanently closed at one end, as seen in Figs. 5 and 6, and at and adjacent its other end is formed or provided with suitable openings 6 and 7 adapted for connection in the case of manifold 4 105 with a water-supply pipe and in the case of manifold 5 with a suitable discharge

pipe. In this connection, it is to be understood that only one set of the manifold openings 6, 7, are employed at the same time, as may best meet the particular arrangement of plant-piping, the other or unused set of said openings being closed by screw-plugs or the like, such as shown at 8 in Fig. 1. In the present illustration, the end-openings 6 of the manifolds are in service 10 and connected with the supply and discharge pipes, the side openings 7 being closed.

On the upper surface of the base-top 1, surrounding each port-opening 3, is an integral finishing rim 9, and disposed upon a pair of the rims 9 for co-operation with their ports 3, and extending transversely of the base, is a combined valve-chamber and cylinder-connecting member or unit 10, the upper faces of the said rims 9 being preferably suitably machined, whereby fluid-tight joints may be conveniently made with the unit-member 10. Each unit-member 10 is substantially an integral hollowed or chambered casting approximately rectangular in shape and is formed adjacent one end and in its under or bottom wall with an aperture or port-opening 11 in open communication with the port 3 of the suction manifold 4. Formed in the upper wall of unit 10, approximately in alinement with opening 11, is a suitable opening, within which is threaded the seat of a suitable valve 12, whose detail is not here shown, but which is preferably of standard spring-seated type, the seat of the valve being preferably so disposed in its said opening as to be screwed "home" in the direction of fluid-flow, thereby obviating its displacement by the action or force of the fluid moved therethrough or by the suction and discharge pressures created by the cylinder-piston. Formed within the unit 10 by an interior integral wall 13, is a chamber 14 in open communication with port-opening 11 and the valve 12. Formed in the unit 10 adjacent its opposite end and also in its under or bottom wall, is an aperture or port-opening 15 in open communication with the port 3 of the discharge manifold 5. Leading 50 from port 15 and opening on to the upper face of the upper wall of unit 10, is a passage 16 formed by an interior integral wall 17. Formed in the upper wall of unit 10 adjacent the open upper end of passage 55 or water-way 16, is a suitable opening, within which is similarly threaded the seat of a suitable valve 18 preferably in all respects like the valve 12 and its seat hereinbefore described. Extending longitudinally within 60 the unit 10, is a passage or water-way 19 having one end opening through the top wall of unit 10 adjacent the valve 12 and being enlarged at its other end to provide a chamber, as at 20, of relatively large ca-

pacity surrounding the valve 18, all as seen 65 particularly in Fig. 3.

Formed in the upper wall of the unit 10 at approximately the longitudinal center thereof, and communicating with the passage or water-way 19, is an opening or aperture 21, which is arranged to receive and provide a seat for the reduced end 22 of an upstanding cylinder 23. In order to form conveniently a fluid-tight joint between the cylinder 23 and its combined valve-chamber 75 and connecting unit 10, the abutting faces of each are preferably suitably machined and the cylinder provided adjacent its lower end with radial feet 24, through which fastening-screws 25 are passed and extended 80 into the unit 10 to rigidly secure the cylinder 23 in its seat 21 and upon the unit 10 in a substantially leak-tight, fully operative manner.

The unit 10 on its upper face surrounding 85 the valves 12 and 18 and the open upper ends of the water-ways 16 and 19 is preferably suitably machined to a smooth surface, and fitted thereupon over the said valves 12 and 18 and the open upper ends of the said 90 water-ways 16 and 19, are housing-members 26—26 having preferably the shape or form best seen in Fig. 3, and which provide connecting-chambers between, respectively, the valve 12 and water-way 19 and the valve 13 95 and the water-way 16.

Each housing-member 26 is provided with a flat upper face, as at 27, to efficiently co-operate with preferably cruciform securing-members 28, one alined pair of arms of each member 28 being adapted to fit and rest upon the flat faces 27 of two adjacent housing-members 26, and the other alined pair of arms of each said member 28 being perforated to receive fastening-bolts 29 105 up-standing from, and screw or otherwise seated at their lower ends in, the base-plate 1, whereby the housing-members 26 are rigidly held in a substantially leak-tight manner upon the units 10 and whereby also the units 10 with their attached cylinders 23 are rigidly held likewise in a substantially leak-tight manner upon the base-plate 1. By the construction described, it will now be evident that the several parts of the pump 110 are adapted for facile assemblage, that the several parts of the sections or units of the pump are substantially standardized and readily interchangeable, and that the parts of any one or all of the sections or units of 115 the pump may be when required conveniently repaired or replaced. As seen particularly in Figs. 1 and 2, each valve-housing member 26 is rigidly held operatively in position in the present pump by one arm 120 of a pair of the cruciform securing-members 28, the outer arms of the end members 28 resting upon suitable lugs 30 pro-

vided or formed on pump-gearing standards 31, which latter upstand from, and are rigidly bolted or otherwise fastened to and upon, the base-plate 1.

5 Mounted for rotation in suitable pillow-blocks 32 forming preferably parts of the standards 31, is a shaft 33 provided within its length with suitable eccentrics 34 connected by straps or the like 35 with pistons 36 corresponding in number to the number of cylinders of the particular pump, the present pump being equipped with three pistons, one for each of the three cylinders 23. By preference, the shaft 33 is driven 10 by a motor 37, whose bed 38 is preferably an integral part of the base of the pump, the belt or other driving connection between the shaft 33 and motor 37 being concealed in the present installation by a safety-guard 39.

In use and operation, assuming the motor to be running and the manifolds 4 and 5 suitably connected with supply and discharge pipes, respectively, the up-stroke of a piston 36 produces a suction which draws the water or other fluid from the manifold 4 and through the communicating ports 3 and 11 into the chamber 14, and then through the valve 12 and water-way 19 into the cylinder of the piston. On the down-stroke of the piston, the pressure produced acts to discharge the water or other fluid therefrom into the water-way 19 and then through the chamber 20, valve 18, passage-way 16, and communicating port-openings 15 and 3 into the manifold 5, and from the manifold 5 to a desired point of discharge. It will be noted that the chambers 14 and 20 provide for a considerable volume of water at the valves 12 and 18, respectively, by reason of which there is a minimum of binding movement at the valves to restrict the flow of the fluid or water therethrough.

There being substantial uniformity in the pump sections or units, my new pumps, by varying the size of the base or the number of cylinders and connecting-parts or ports, may be selectively built to any desired capacity to meet the requirements of different installations. The pump, as a whole, as will now be evident, is most simple and compact in form and construction, it is highly efficient in operation with little or no leakage, and its cost of production, as well as also 55 its operating or maintenance cost, is exceedingly low. To neatly drain from the pump any fluid or water which may escape or splash from the cylinder or cylinders, the base-plate 1 is preferably longitudinally channeled, as at 40, upon its upper face and beneath the cylinder or cylinders, which channel extends to one end of the base and is there suitably connected to a pipe 41 leading to a desired point of discharge.

60 65 I am aware that changes in the form, con-

struction, arrangement, and combination of the several parts of my new pump may be made and substituted for those herein shown and described without departing from the nature and principle of my invention.

Having thus described my invention, what I claim and desire to secure by Letters Patent is:

1. A pump of the class described, including a base plate unitarily formed and provided with suction and discharge manifolds adapted for connection with the supply and discharge sides of the pump respectively, the manifolds being disposed side by side in parallel relation on the under side of the plate and the plate being provided with port-apertures communicating with the manifolds.

2. A pump of the class described including, as a unit, a base plate formed selectively with a number of pairs of suction and discharge ports disposed in alining rows and adapted for communication with a corresponding number of cylinders, and suction and discharge manifolds having communication, respectively, with said rows of ports and adapted for connection with the supply and discharge sides of the pump, respectively, the manifolds being integral with, and disposed side by side in parallel relation on the under side of the plate.

3. A pump of the class described including, in combination, a base-plate, suction and discharge manifolds both disposed on the under side of the plate, and a unit-port-member fitting upon the upper side of the plate and having inlet and outlet ports adapted for communication with said manifolds, respectively, said member having a suction-and-discharge cylinder-port intermediate of, and adapted for communication with, said inlet and outlet ports.

4. A pump of the class described, including, in combination, a base-plate, suction and discharge manifolds both disposed on the under side of the plate, and a unit-port member fitting upon the upper side of the plate and having inlet and outlet ports adapted for communication with said manifolds, respectively, said member having a suction-and-discharge cylinder-port intermediate said inlet and outlet ports and a fluid-way adapted to provide communication between the cylinder-port and both said inlet and outlet ports.

5. A pump of the class described including, in combination, a base-plate, suction and discharge manifolds both disposed on the under side of the plate, a unit-port member fitting upon the upper side of the plate, said member having inlet and outlet ports adapted for communication with said manifolds, respectively, and a fluid-way adapted to provide communication between said ports, valves seated in said member for con-

trolling communication between said way and said ports, and valve-housings seated upon said member and providing communicating-chambers between said valve-controlled ports and said way.

6. A pump of the class described including, in combination, a base-plate, suction and discharge manifolds disposed on the under side of the plate, a unit-port-member fitting upon the upper side of the base-plate, the port-member being adapted for communication with both said manifolds, and means for securing the port-member to the base-plate.

15 7. A pump of the class described including, in combination, a base-plate, suction and discharge manifolds disposed on the under side of the plate, a unit-port-member fitting upon the upper side of the base-plate, an upright cylinder mounted on the port-member, the port-member being adapted to provide communication between the cylinder and both said manifolds, and means for securing the port-member and its cylinder to 25 the base-plate.

8. A pump of the class described including, in combination, a base-plate, suction and discharge manifolds, a unit-port member fitting upon the plate, said member having 30 inlet and outlet ports adapted for communication with said manifolds, respectively, and a fluid-way adapted to provide communication between said ports, valves seated in said member for controlling communication between said way and said ports, 35 valve-housings seated upon said member and providing communicating-chambers between said valve-controlled ports and said way, and means for conjointly clamping 40 said housings upon said member and said member upon said base-plate.

9. A multicylinder pump of the class described including a base, suction and discharge manifolds, and a plurality of cylin-

ders, in combination with a plurality of 45 valve-containing port-members mounted upon the base and adapted, respectively, to provide valve-controlled communication between the cylinders and the manifolds, valve-housings mounted upon said members, 50 and means including a yoke engaging the valve-housings of two adjacent members for rigidly securing the valve-housings operatively upon the members and the members operatively upon the base.

10. A pump of the class described including, in combination, a base-plate, suction and discharge manifolds disposed on the under side of the plate, a unit-port-member fitting upon the upper side of the base-plate, and an upright cylinder mounted on 60 the port-member, the port-member being adapted to provide communication between the cylinder and both said manifolds.

11. A pump of the class described including, in combination, a base-plate, suction and discharge manifolds disposed on the under side of the plate, a unit-port-member fitting upon the upper side of the base-plate, an upright cylinder mounted on the port-member, the port-member being adapted to provide communication between the cylinder and both said manifolds, and valves seated 70 in the port-member for controlling communication between the cylinder and both said manifolds.

12. A pump of the class described including, in combination, suction and discharge manifolds, a unit port and valve-containing-member disposed upon the manifolds, and a 80 cylinder disposed in upright position on said member, the member being adapted to provide communication between the cylinder and both the manifolds.

In witness whereof, I have signed my 85 name to this specification.

GEORGE McD. JOHNS.
